CLAIM

The ornamental design for a counter display unit for cosmetics, as shown.

DESCRIPTION

FIG. 1 is a perspective view of a counter display unit for cosmetics showing my new design;

FIG. 2 is a side elevational view taken from the left of FIG. 1.

FIG. 3 is a top plan view;

FIG. 4 is a front elevation view; and

FIG. 5 is a rear elevational view thereof.
